(57) **CLAIM**

The ornamental design for an adjustable rifle stock, as shown and described.

DESCRIPTION

FIG. 1 is an upper left perspective view taken from the front of an adjustable rifle stock showing my new design; FIG. 2 is a lower right perspective view taken from the front thereof;

FIG. 3 is a top view thereof;

FIG. 4 is a right side elevation view thereof;

FIG. 5 is a left side elevation view thereof;

FIG. 6 is a bottom view thereof;

FIG. 7 is a front end elevation view thereof; and,

FIG. 8 is a rear end elevation view thereof.

The broken line showing of portions of the adjustable rifle stock forms no part of the claimed design.
